GASOLINE DISPENSING APPARATUS

Emil C. Baber, Los Angeles, Calif., assignor to
Lyman Wood Davis, Los Angeles, Calif.

Application April 28, 1936, Serial No. 76,786

28 Claims. (Cl. 194—82)

My invention relates to a combination coin controlled and manually controlled liquid dispensing apparatus and as at present the principal field of use appears to be for dispensing gasoline, I have designated the invention as a gasoline dispensing apparatus.

One of the main objects and features of my invention is a coin operated device which controls the operation of the liquid dispenser and is of such a type that it may be installed with a number of different types of liquid measuring and dispensing appliances, these being known in the trade as gasoline pumps. For convenience of description the device and the combined apparatus is therefore designated as a gasoline dispenser or gasoline pump mechanism. In the present set up of my invention in view of the fact that most of the so-called gasoline pumps are electrically actuated, that is a motor is operated electrically, the motor driving a pump and the gasoline flowing through a meter, the coin actuating mechanism is designed to operate an electric switch for closing and opening the circuit of the motor. A further feature of my invention is that the release of the coin-actuating mechanism is utilized to close the electric switch of the motor circuit, then by means of a measuring register actuated in connection with the gasoline meter the flow of gasoline is shut off after dispensing an amount corresponding to the purchase price of a particular coin used in the machine.

These coin actuated gasoline dispensing pumps have a field of operation in which the pump may be manually controlled when there is an attendant at a gasoline dispensing station or when the attendant is absent for instance, over night, the coin controlled part of the mechanism may be brought into operation to dispense the gasoline in accordance with the value of different coins.

Another main object and feature of my invention is a machine which will operate on coins of different value, for instance using ten cent pieces, twenty five or fifty cent coins designated hereunder as dimes, quarters and half dollars, each of which permits the operation of the device and dispensing of gasoline to the value of the individual coin if only one coin is inserted in one of the coin chutes. The machine is provided with a plurality of coin chutes, thus in the instance described there being a chute for the dimes, one for the quarter dollars and one for the half dollars. Manifestly if desired, there could be a chute for nickels and another chute for dollars, but such would unnecessarily complicate the machine.

Another object and feature of my invention is

that coins for instance of the three values, that is of all the values for which the machine is designed, can be inserted in the respective coin chutes and the machine then operated in which case there is first discharged a quantity of gasoline to the value of a dime, on a second operation to the value of the quarter dollar and on the third operation to the value of the half dollar. A further detail feature is in the employment of a manually operated starting device such as a lever so that the person making the purchase, after inserting the coins, by operating this lever or other device, starts the operation for each of the coins used.

Another object and feature of my invention is that with my machine a plurality of coins of the same value may be placed in the proper coin chute for such value, therefore for instance, if a number of dimes are used the purchaser may start the machine to dispense separate quantities of gasoline corresponding in value to each of the coins until all of the dimes have been exhausted. Then if he has placed a plurality of quarter dollars and/or half dollars, the purchaser starts the machine to dispense individual quantities corresponding to these coins.

In connection with the use of a plurality of coins of the same value, each in its own chute, a detail feature of my invention relates to a retaining device which permits only the lowermost coin of a group to function in the control of the switch, then as such lowermost coin is discharged to a coin receiving box, the coin next above comes into operation, the remaining coins being retained until in a sequence all of the coins of the one value have been utilized. This feature makes it necessary that the machine dispense to the purchaser gasoline to the value of the coins inserted in the coin chutes and as the purchaser may insert a sufficient number of coins for the amount of gasoline he wishes to purchase before actuating the machine, the purchaser may quickly obtain the full quantity of gasoline without having to insert a coin for each operation of the machine.

A further main object of my invention relates to the mechanism for changing the price value so that different quantities of gasoline will be dispensed using the coins above designated, this quantity depending on the price per gallon of the gasoline; thus manifestly when the price is low the purchaser secures a greater quantity for each individual coin than he would if the price were high. A feature of this price regulating mechanism resides in the simplicity and positive features by which the exact quantities to be dis-

pensed at any standard price may be calculated and set on a register. For convenience in my present machine I have made changes of price in one-half cents, starting with a low price of five cents per gallon and having the present machine graduated in one-half cent values to a maximum price of forty cents per gallon. Of course manifestly these values may be changed.

A further main feature of my invention is an inter-linking of the price graduated dispensing register which is operated by the gasoline meter with the switch mechanism which is set in closed switch position by the coin actuated mechanism so that when the exact quantity corresponding to a particular coin has passed through the meter and actuated the register, the register causes the opening of the switch and thus a stoppage of the motor, the meter and hence the flow of gasoline.

A further feature of my invention as it relates to the price register is in the employment of a drum or cylinder which is mounted to have vertical movement controlled by a screw feed. This cylinder is designed to make one rotation for each gallon of gasoline dispensed and in my present machine the length of the drum is such that it may make ten rotations for a given movement in an axial direction and thus dispense ten gallons, should a coin be inserted to the value of ten gallons.

Another detail feature is that the use of a drum or cylinder of this type which both rotates and has a movement in an axial direction resides in having a large number of sockets in the periphery of the drum and in these sockets are placed trigger operating pins, one for the dime, another for the quarter and a third for the half dollar. The various sockets are numbered in accordance with calculations made as to the quantity to be dispensed for different prices, then by means of a prepared chart or table the attendant may place these trigger operating pins in the correct socket.

One of the difficulties encountered in coin controlled gasoline dispensing pumps resides in a flow of gasoline due to pressure sometimes called coasting of the machine when the gasoline should be shut off. I overcome this difficulty by employing a positively operated valve which valve is open in conjunction with the closing of the circuit through the control switch and is automatically closed at substantially the time the switch is open so that at the instant the current of the electric motor is opened, the valve closes and prevents any further dispensing of the gasoline which might occur by the coasting rotation of the motor or by a built up pressure in the pump, thus with my invention I secure a more accurate dispensing of the gasoline as to the quantity for the particular coin used.

My invention is illustrated in connection with the accompanying drawings in which—

Figure 1 shows the upper part of a so-called gasoline pump, one of the side panels being cut away to expose in elevation part of the meter, a clutch, the quantity registering drum, a side elevation of the coin controlled and actuated mechanism and other detail.

Figure 2 is a horizontal section on the line 2—2 of Figure 1 downwardly in the direction of the arrows showing the top of the quantity registering drum and a plan of the coin controlled mechanism.

Figure 3 is a vertical section on the line 3—3 of Figure 2 in the direction of the arrows showing part of the quantity registering drum in elevation and a side elevation of a part of the coin controlled mechanism.

Figure 4 is a horizontal section on a reduced scale illustrating the double levers for closing and opening the clutch between the meter and the quantity registering drum, being taken on the section lines 4—4 of Figure 3 in the direction of the arrows.

Figure 5 is a horizontal section on the line 5—5 of Figure 3 in the direction of the arrows through the quick acting clutch.

Figure 6 is a vertical section on the line 6—6 of Figure 3 in the direction of the arrows and may be considered substantially as an elevation of the inside portion of the coin controlled mechanism.

Figure 7 is a horizontal section on the line 7—7 of Figure 6 in the direction of the arrows.

Figure 8 is a vertical section on the line 8—8 of Figure 1 or 3 in the direction of the arrows and may be considered an elevation partly broken away of the outside of the coin controlled mechanism.

Figure 9 is a vertical section on the line 9—9 of Figure 8 taken in the direction of the arrows, illustrating a coin with the sliding members actuated through the medium of the coin.

Figure 10 is an end elevation of the part of the coin controlled mechanism taken in the direction of the arrow 10 of Figure 8 illustrating the main electric switch control mechanism in the open switch position prior to a downward movement of the coin slides which are manually operated.

Figure 11 is a view similar to Figure 10 showing the main switch control mechanism in its lock position for an open switch when the coin slides are in their lowermost position and prior to their manual release for a return movement.

Figure 12 is a view similar to Figures 10 and 11 showing the position of the switch actuated mechanism in the position for a closed switch circuit, this mechanism being held in this position during the dispensing of gasoline.

Figure 13 is a vertical section on the line 13—13 of Figure 8 on a reduced scale through the coin chute of one of the coin slides.

In my invention, referring first to Figure 1, a suitable stand or housing 11 is utilized and which may be of a common type used in so-called gasoline pumps. In this stand is located a liquid meter 12. This meter receives liquid from a liquid pump and the pump is usually actuated by an electric motor. My invention as illustrated is dependent on controlling the electric motor for operating the pump and hence the meter, my coin controlled mechanism being designed for operation to close the main electric switch supplying current to the motor and the quantity registering device being operative to release part of the coin controlled mechanism to cause the closing of the switch. In the illustration of Figure 1 the gasoline line is discharged through a discharge pipe 13 from the meter which leads upwardly through a control valve 14 and is then led from the valve by a pipe 15 to a flexible hose 16 and then to a nozzle 17 used for discharging the gasoline into a tank. This nozzle has a normally shut off valve which is opened by actuating the finger grip lever 18. A vertical shaft 19 leads upwardly from the meter and is connected to a clutch designated by the assembly numeral 20 and from this clutch there is an upper shaft 21 which operates the hands 22 operating over a dial 23 to limit the quantity of gasoline dispensed at any operation of the machine. These hands may be returned to the zero position by any standard mechanism now used for so returning the hands.

The coin actuated mechanism designated generally by the assembly numeral 30 employs a

coin inserting opening 31 (note Figure 1) from which the coin drops through any suitable coin guide 32 and passes through an opening 33 in the top plate 34 of the main coin slide mechanism designated by the assembly numeral 35 (note particularly Figures 9 and 13). This coin slide mechanism is mounted in a frame having the top plate 34, opposite side plates 36 and 37 (note Figures 6, 7, and 8) and a bottom plate 38. The side plates 36 and 37 each have an inwardly extending longitudinal guide rib 39 adjacent the outside edge and an internal guide plate 40 and extending between the top and bottom plates 34 and 38, there are connected vertical guide plates 41 and 42 (note Figure 7).

Between the marginal guide plates 40 and the vertical guide plates 41 and 42, there are three coin chute slides designated 43, 44 and 45 (note Figure 7). Each of these has a chute designated 46, 47 and 48 for coins, 46 being for dimes, 47 for quarter dollars and 48 for half dollars. It is necessary to lead the coins to these various chutes that there are three of the insert openings or slots 31, one for each coin and three of the coin guides 32. The bottom end of each chute for the coins has a curved end 49 (note Figures 9 and 13) which divert the coins laterally. These coin chute slides 43, 44 and 45 are formed with laterally extending guide ribs 50 on their opposite sides, engaging the various fixed plates 40, 41 and 42. These slides are normally held in their uppermost position by tension springs 51 which have their upper ends secured to eyes 52 on the top plate 34 of the frame construction 35 and their lower ends connected to projecting studs 53 adjacent the lower portion of each of the slides 43, 44 and 45, there being two springs shown for each coin slide construction.

Cooperating with the vertically slidable coin chute slides 43, 44 and 45, there is a common depressing slide designated by the assembly numeral 60 (note particularly Figures 7, 8 and 9). Said depressing slide comprises outside vertical frame members 61 on each side, and a top transverse plate 62 having rubber bumpers 63 thereon to contact the top plate 34 of the frame 35. There is a substantial horizontal block 64 at the bottom connecting the side frames 61 and having outside cover plates 65 and 66 (note Figure 9). The inner surface 67 of the horizontal block 64 is vertical except for the coin notches 68. These curved notches are diagonally opposite the curved ends 49 of the several coin chutes. Thin cover plates 69 are provided on the slide chute guides 43, 44 and 45 forming edge covers for the coin chutes 46, 47 and 48. Therefore when coins are dropped in any one of the chutes they lodge in the coin pocket designated 70 (note Figures 9 and 13) between the upper block 64 and the lower portion of the coin slides. Vertical rods 71 and 72 are connected to the transverse block 64 and extend downwardly through perforations 73 in the bottom plate 38 of the frame 35. At the front of this plate there is a tapered bar 74 for the purpose of deflecting coins as they are discharged into a coin receiving box. A cross head 75 in the form of a plate connects the two rods 71 and 72. The manually operated device to start the actuation of the machines is designated by the assembly numeral 80 (note Figures 1 and 8). This utilizes a hand actuated lever 81 which is secured to a shaft 82 which is journaled in a suitable structure on one side of the stand or

housing 11, preferably the side having the hose 16. A rocking arm 83 is secured to the shaft 82 preferably by means of a sleeve 84 pinned on the shaft and a roller 85 is carried by the end of the arm and rests on the top of the cross-head 75. Therefore, when there is a coin in any one of the coin pockets 70 and the lever is operated to depress the cross-head 75 by the medium of the rods 71 and 72, the slide depressing frame 60 is moved downwardly and by pressure transmitted through a coin in a pocket, gives a downward movement to the particular coin chute slide, either 43, 44 or 45, according to which slide contains the coin; therefore the machine may be operated by a single coin in one of the coin slides.

Detent devices for retaining coin chute slides 43, 44 or 45 in their lowermost position are designated by the assembly numeral 90 (note particularly Figures 3, 9, 10, 11 and 13). Each of 20 these slides has a detent thereon indicated 91 for the dimes, 92 for the quarter dollars and 93 for the half dollars. Each of these has a wedging front edge 94, these being constructed on a bevel and each has a horizontal upper surface 95 and thereby each has a projecting upper corner 96. It will be noted by reference particularly to Figure 7, that the detent 91 projects further from the face of the coin chute slides than the quarter dollar or the half dollar having the least projection. For convenience of assembly and locating these detents they are attached to the side of each of their respective slides, 43, 44 and 45, as shown in Figure 7. 30 These slide-detents are designed to co-act with a rocking latch designated 100; such latch has 35 end pivot pins in the form of screws or bolts 101, which are journaled in projecting ears 102, these being preferably constructed on straps 103 projecting from the lower part of the side plates 40 40 and 31. There are short arms 104 and 105 secured to each of the pivot pins preferably by having such pins screw-threaded therein as shown in Figure 6 and at the upper end of each of the arms 104 and 105 there are parallel tilt- 45 45 plates 106 and 107, the manner of attachment preferably being by having upwardly projecting ears 108 (note Figure 9) on the arms 104 and 105, a downwardly extending tongue 109 on each of the plates 106 and 107 and a 50 pivot pin 110 extending through the ears of the tongue. The plate 107 has a downwardly extending projection or finger 111 which engages the inside of the arm 105 so that this arm is only free to rock on its pivot in the direction 55 of the arrow 112 (note Figure 6). A tension spring 113 is secured to an eye 114 at the upper inside portion of the plate 107 and to a second eye 115 attached to the inside of the arm 104; therefore this spring normally holds the plate 60 107 in its upward position.

The plates 106 and 107 are connected by a latching bar 116 (note Figures 6, 7, 9, 10, 11 and 13). The connection is preferably by having a pair of spaced ears 117 on each end of the bar 65 116, interengaging with an upper tongue 118 on each of the plates 106 and 107 and these being connected by pintle pins 119 (note particularly Figure 6). This latching bar 116 has either a continuous corner notch 120 or a series of these 70 notches designed to engage the upper corner 96 of each of the detents 91, 92 and 93 (note Figures 11 and 13). Retraction springs 121 are connected by pins 122 to each of the plates 106 75 and 107 and to pins 123 attached to the sides 75

- 36 and 37; these springs draw the upper end of the trigger frame towards the coin slides and the wedging detents mounted thereon and on account of the tension spring 113 normally maintaining the plate 107 vertical through the connection of the latching bar 116 to the plate 106, this is also maintained vertical. Therefore as any one of the slides either 43, 44, or 45, is moved downwardly by having a coin therein, the detent 5 on such slide pivots the latch mechanism outwardly due to the wedge surface 94 until the corner 96 slips into the notch 120; the upper surface 95 of the detent engaging the underside of the latching bar, restrains the particular coin chute either 43, 44 or 45 from moving upwardly under the action of the retraction springs 51.
- It is manifest therefore that as the detents project a greater distance from the coin chute 20 slides, that when the latching bar is engaged by the detent 91 for dimes it will be spaced outwardly from the frame of the slides a greater distance than if the latching bar is engaged by the detent 93 for the half dollars; the detent 25 92 for the quarter dollars is intermediate. The latching bar 116 is provided with releasing notches 124, 125 and 126 (note Figure 7) positioned contiguous to the detents 91, 92 and 93, respectively, and on the side remote from the 30 tilting plate 107. Projecting from the front edge 127 of the latching bar 116 there is a releasing stud 128; this is preferably part of a plate 129 which is attached by screws 130 to the top surface of the latching bar 116. This stud has a vertical abutment shoulder 131 and a sloping rear side 132.
- The dispensing of gasoline is not started by depressing the coin slides and holding these slides in their lowermost position, but the dispensing is only started after release of the coins on the upward movement of the common depressing slide 60. The control mechanism for actuating the switch is designated as the switch control mechanism and designated by the assembly numeral 140 (note particularly Figures 6, 8, 9, 11 and 12). The electric switch 141 is of a standard type and may be of a snap-switch type; the particular form of switch does not enter into my invention as I use a switch which is now common for this purpose. The switch, however, is actuated for closing and opening same by a reciprocating rod 142. This is pivotally connected to a link 143 and the link is connected to trigger lever 144. This lever is pivotally mounted on a stud 145 which projects laterally from the frame 35 preferably from the side plate 37 (note Figure 8). This trigger lever has a projecting nose 146 and is normally pulled downwardly by a tension spring 147 connected 50 at 148 to the trigger lever and at 149 to a pin projecting from the slide plate 37. The link 143 is shown as pivotally connected to the trigger lever at 150 intermediate the pivot stud 145 and the connection of the spring 147. This lever has a notch 151 which is formed adjacent the end of the lever remote from the nose 146.
- A pivoted hook 152 is pivoted at 153 on a plate or the like 154, attached to the side plate 37; such hook has a shoulder 155 adjacent its upper end 55 adapted to engage the nose 146 of the trigger lever 144 and by means of the tension spring 156 which is attached at 157 to the upper end of the hook and at 158 to the side plate 37, the detent arm is constantly under a pull towards the trigger lever. When the depressing slide
- designated 60 is in its uppermost position a cam plate 159, which is secured to the horizontal block 64 or to the plate 65 (shown particularly in Figure 8), holds the hook 152 upwardly; this cam plate has a sloping wedging surface 160 which engages a projecting wedge lug 161 on the hook 152; thus when this slide having the bar 64 is in its upper position the hook 152 is in the position of Figure 10. On the downward movement of the two slides with a coin engaged therebetween, the cam plate 159 moves downwardly to the position of Figure 11 and the spring 156 on the first release of the wedging lug 161 brings the shoulder 155 over the nose 146 of the trigger 144 and retains such trigger in the position of Figure 11. When the trigger is in the positions of Figures 10 and 11, the switch 141 is open, that is, there is no electric connection for energizing the electric motor for driving the fluid pump.
- Each of the coin slides 43, 44 and 45 has a projecting pin 165 indicated at 165, 166, and 167 (note Figure 6) so that each of said pins engages a cross bar 168 which is secured to the outer end of two arms 169 and 170, one of which is pivoted on the stud 145 extending from the plate 37 and the other is pivoted to a similar stud 171 attached to the side plate 36. The arm 170 forms a portion of a bell-crank whose other, vertically extended arm 195 is urged outwardly by a retraction-spring 202 acting thereon through a lever 197 and a connected rod-link 196 to yieldingly maintain the arms 169 and 170 in their uppermost position. The arm 169 is indicated as having a pin 172 projecting therefrom. Therefore, on the downward movement of the depressing slide 60 which carries any one of the coin chute slides 43, 44 or 45 downwardly, the arm 169 is moved downwardly from the position of Figure 10 to the position of Figure 11 in opposition to the spring 202 and as the slide 43, 44 or 45, which carries the coin, is held downwardly by the medium of the latching bar 116 engaging one of the detents 91, 92 or 93, the pivoted arms 169 and 170 are retained in the position of Figure 11. On release of the coin when the operator of the machine again allows upward movement of the operating arm 81, the coin depressing slide 60 with the cross block 64 moves upwardly again bringing the cam plate 159 into action against the wedge lug 161, thereby moving the hook 152 outwardly from the position of Figure 11 to the position of Figure 12. This action causes the release of the trigger lever 144 by the shoulder 155 of the hook being moved away from the nose 146 of this trigger lever, then the tension spring 147 gives a quick downward movement to this trigger lever 144 and hence through the medium of the link 143 and the rod 142 operates the main switch 141 which snaps to its closed circuit position, the electric motor is then energized for operating the pump for delivering gasoline or other fluid through the meter to the discharge nozzle 17.
- After a pre-determined quantity of liquid has been dispensed the respective detent is released to allow upward movement of the coin slides, 43, 44 or 45. This action so far as the latch mechanism is concerned, is accomplished through an end pressure in the direction of the arrow 175 (note Figures 6 and 7) effected by the engagement of a projecting portion of a rotatable registering drum 230, hereinafter described, with the shoulder face 131 of the stud 128. Said stud is secured to the latching bar 116, which bar as

above mentioned has engaged one of the detents 91, 92 or 93, as shown in Figures 11 and 13; therefore, when the latching bar is forced in the direction of the arrow 115 it swings the plates 106 and 107 on their pivots in the direction of the arrow 112 at Figure 6. This movement is sufficient to align one of the notches 124, 125 or 126 on latching bar 116 (note Figure 7) with the particular detent engaging such latching bar, therefore as the engaged detent may move upwardly through one of these notches, the particular slide, either 43, 44 or 45, again moves upwardly, this admitting of the upward movement of the pivot arms 169 and 170 through the action of the spring 202 which brings the pin 172 attached to such arm, into the notch 151 of the trigger lever 144. This engagement is shown in Figure 12 and moves the trigger arm upwardly to the position of Figure 10, thus stretching or tensioning the pull-down spring 147. As this action pulls upwardly on the rod 142, the operation is to open the switch 141 which by a mechanism in the switch snaps quickly to its open circuit position. Hence after the pre-determined quantity of liquid has been dispensed, the electric motor is quickly de-energized.

As above mentioned in the objects of the invention, a person desiring to purchase gasoline may deposit a number of coins of the same value in any one of the chutes designed for such coin, but on actuation of the hand lever 81 he purchases a quantity of gasoline corresponding in value to the lowermost coin in the coin chute which coin only is released. The retention mechanism for the other coins in the chute is designated as a coin retainer device having the assembly numeral 180 (note particularly Figures 6, 7, 8 and 9). In one side of each of the coin sliding chutes 43, 44 and 45, adjacent the chutes 46, 47 and 48, there are perforations indicated at 181, 182 and 183 (note Figure 7). There are three similar coin retaining pins designated 184 (note Figures 7 and 8), each attached to a leaf spring 185 and such leaf spring being secured as indicated at 186 to a side of the particular coin chute with which it cooperates. Each of these springs has a U shaped retraction yoke 187 (note Figures 6 and 7) attached thereto and designed to be engaged by the lower tapered end 188 of a firmly fixed finger 189, attached as indicated at 190 to the top plate 34 of the frame construction 35, hence such fingers which are quite stiff, are prevented from movement.

The operation of the coin retainer device 180 is as follows: When the coin slides 43, 44 or 45 are in their uppermost position as shown in Figures 8 and 9, the yoke 187 on the particular spring 185 is engaged by the tapered finger end 188, this bending the spring outwardly and retracting the retaining pins 184 from the particular perforation 181, 182 or 183 as shown in Figures 7 and 8, therefore coins may drop freely in the coin chutes until engaged in the coin pocket 70. Then, on the downward movement of the coin chute slides 43, 44 or 45 through the medium of the depressing slide structure 60, the yoke 187 slides downwardly on the tapered finger end 188, thus allowing the pin 184 to be thrust in one of the perforations 181, 182 or 183 into the position shown in Figure 13 to engage a coin above the lowermost coin and hence support all the rest of the coins in this particular chute so that when the lowermost coin is discharged, the remaining coins are held in position until the coin slides move upwardly when the finger end 188 again comes into operation to

retract the pin 184 and release the stack of coins in any particular coin chute so that the lowermost coin again comes into a coin pocket 70, the remaining coins thereabove being held in the coin chute.

As above mentioned in the objects of the invention, it is not necessary for a person operating the machine to insert only one coin of any denomination at a time, but he may insert coins of two or more of the denominations and moreover the operator, as above described, may insert a stack of coins in any one chute. However, in the dispensing of the liquid on each operation of the starting lever 81, liquid to the value of a single lowest value coin in the machine actuates the machine first and then in succession all of the lowest value coins are used up, the other coins being retained in their coin chutes, for instance, presuming dimes, quarter and half dollars are inserted in their respective stacks, then on the downward movement of the depressing slide 60, as there is a coin in each coin pocket, all of the coin slides 43, 44 and 45 are depressed. However, as the detent 91 for the dimes projects a greater distance from the slides than the other detents 92 and 93, the rocking latch device 100 having the latching bar 116, is only engaged by the detent 91 on the dime slide, therefore only this slide is held downwardly when the lever 81 is moved up and the quarter and half dollars are retained in their particular coin pocket 70 due to the depressing slide 60 moving upwardly with the quarter and half dollar slides 44 and 45.

The machine is actuated or started each time by the lever 81 until all of the dimes are exhausted, then the quarter dollars come into action, the dime slide 43 remaining stationary in its upper position as there is no coin to depress such slide. The machine is then operated by a movement of the lever 81 for each of the quarter dollars until the stack of quarter dollars is used up, the machine at each operation vending a quantity of gasoline corresponding to the value of the coin. Then when all the quarter dollars have been used up, the half dollars operate to control the machine, in which case both the dime and quarter dollar chutes 43 and 44 remain stationary in their uppermost position. Then, when the half dollars are exhausted the machine cannot operate until a further supply of coins are placed in the machine, either by the same or another operator.

The control valve 14 is operated by the following mechanism: The arm 170 is constructed in the manner of a bell crank, having an upwardly extending crank arm 195 (note Figure 1) which is pivotally connected by a stiff rod 196 to a valve actuating lever 197; this lever is pivoted at 198 on a support 199 attached by a clamp or other device, 200, to the body of the valve. The valve stem 201 is connected to the lever 197. A retraction spring 202 connected to the lever 197 and to a fixed part of the frame or casing structure 11 normally retracts this lever and maintains the valve in its closed position. Therefore, as soon as any one of the coin chute slides 43, 44 or 45 moves downwardly, one of the pins 165, 166 or 167 causes the operation of this bell crank, having the arms 170 and 195, this giving a thrust on the rod 196, opens the valve. This valve is therefore automatically closed as soon as any one of these pins moves upwardly by means of the retraction spring 202. When it is desired to operate the gasoline pump manually, that is cutting out the coin control mechanism, the operator may remove a hand hole

plate 205 in the housing (note Figure 1) and pull on the link 206 which is connected to the lever 197. This link normally rests and slides on an upturned finger 207 mounted on a stand 208 secured to a fixed part of the machine. The link has an eye 209 which fits over a pin 210 on the upper part of the stand, therefore, when the link is pulled towards the hand hole and the eye 209 engaged with the pin 210, the valve 14 is opened and maintained in the opened position; hence in dispensing gasoline the operator must manipulate the valve operated by the finger grip lever 18. The quantity registering mechanism includes the meter 12 which actuates the vertical shaft 19, the clutch 20 and the quantity registering device designated by the assembly numeral 230. The clutch 20 is actuated through the medium of a clutch operating lever 231 (note Figures 1, 3 and 4). This lever is pivoted on upright posts 232 which extend downwardly from the partition plate or frame 233 located in the housing above the clutch. This lever has a yoke end 234 with inturned fingers 235 engaging a collar 236 on the sliding disk member 237 of the clutch. The opposite end of the lever 238 has three upwardly extending studs 239 which pass upwardly through the bottom plate 38 and are positioned to be engaged by any one of the coin chute slides 43, 44 and 45 when such slide is depressed thereby depressing one end of the lever and sliding the member 237 upwardly to release the clutch. This clutch may be of any suitable type, however, I find it convenient to have a positive release clutch in which a collar 240 secured to the meter shaft 19 has a disk 241 formed integral therewith in which there are a plurality of pivoted dogs 242, each pivoted at 243 to the disk and each having an upwardly extending tapered pin 244 which is engaged by the sloping periphery 245 of the sliding disk 237. This forces the dogs outwardly against the tension of the ring like tension spring 246. When the sliding member 237 is lifted the dogs are forced inwardly to bring their prongs 247 into engagement with the teeth 248 on a hub 249 which is secured to a flange 249' of a hollow shaft 250. Manifestly when the sliding disk 237 is lowered to the position of Figure 3 the clutch is open as shown in Figure 5.

The upper shaft 21 extends downwardly through the hollow shaft 250 and is secured to the collar 240 by a set screw 251 or the like. The sliding disk 237 of the clutch is rotatively mounted on a cylindrical section 252 of the hollow shaft 250, but the upper portion of this shaft above the transverse partition 233 is square in cross section as indicated at 253.

A frame formed with a plurality of posts 260 extends upwardly from the partition plate 233 and has an upper frame 261 to which is secured a fixed nut 262. This nut has square threads and meshes with the hollow screw 263. This screw is square on its inside surface and slides vertically on the squared hollow shaft 250. The upper part of the screw has a head 264 in the form of a disk and to this is attached the drum 265, this drum having a flat or circular head or upper member 266 and a cylindrical peripheral wall 267. The drum is open at the bottom as indicated at 268 so that it may move up and down over the frame having the posts 260.

The manner of operation of the drum 265 to develop a downward movement is as follows: When the clutch is closed, that is, when any one of the coin chute slides 43, 44 and 45 is in its lowermost position and held in such position,

there is a driving connection between the vertical shaft 19 from the meter through the closed clutch to the hollow shaft 250. As this shaft is square it drives the screw 263 and as this screw meshes with the stationary nut 262, such rotation gives a downward movement to the drum as a whole. The relationship is such that the meter shaft 19 makes one complete rotation when one gallon of liquid passes therethrough and through the constant connection to the upper shaft 21 the hand 22 of the dial 23 indicates a flow of one gallon. In the present illustration the drum may make ten rotations and therefore with the present set up ten gallons can be dispensed at once operation of the drum 265.

The return mechanism for causing the elevation of the drum after dispensing of a quantity of fluid is by the employment of a reel 275 which is secured to the upper part 276 of the squared hollow shaft 250 (note Figure 3) and on this reel is wound a cable 277. Such cable leads over a series of idler or change of direction pulleys 278 and on the end of the cable there is a weight 179, thus, when the clutch 20 is opened on the upward movement of one of the coin chute slides 43, 44 and 45 which has been held down, there is no positive drive to the squared hollow shaft 250, the counterweight 279 giving a tension on the cable 277 tends to unwind such cable from the reel 275. Such opening of the clutch 20 is caused by the weight of the sliding member 237 engaging and spreading the dogs 242 when the upward travel of the coin chute slides release the lever 231. This rotates the drum 265 in a reverse direction and causes the screw 263 to thread or move the drum upwardly relative to the stationary screw 262 and bring this drum into the elevated position as shown in Figure 3. The drum is brought to a positive stop in its elevated position by means of a stop arm 285 (note particularly Figures 1 and 2) which is attached to the top plate 34 of the frame construction 35 and has a projecting end 286 which is contacted by a rubber stop lug 287 secured to the circular head 266 of the drum 265.

A suitable manner for graduating the cylindrical wall 267 of the drum 265 for vending different specific quantities of liquid such as gasoline for various selling prices is as follows: the drum is provided with a plurality of screw threaded sockets 290 in which there are three studs. The shortest stud 291 is for the quantity dispensed for ten cents, that is, by inserting one dime in the dime chute. The stud of intermediate length indicated at 292 is for vending twenty five cents worth of gasoline on the insertion of one quarter dollar in the coin chute. The longest stud 293 is for vending fifty cents worth of gasoline by the insertion of a half dollar in its proper chute. These studs are inserted in screw threaded sockets 290. Manifestly as the drum 265 moves downwardly in dispensing gasoline the dime stud 291 will be in the lowermost position on the drum, the quarter dollar stud 292 in the next highest position and the half dollar stud 293 in the highest position. These studs are so regulated in length that when the dime coin chute 43 is operating and as the dime detent 91 projects to the greatest distance, the shortest stud on the drum co-acts with the stud 128 on the latching bar 116. When the quarter dollar chute 44 is functioning the stud 128 projects its medium distance and is engaged by the quarter stud 292 on the drum. The least projection is given to the stud 128 when the half dollar chute 75

45 is operating and in such case the half dollar stud 293, which is the longest, operates to trip the latching bar 116 and the latch assembly controlled thereby.

5 The following is given as an instance of the manner in which the drum 265 may be graduated for dispensing quantities measured in United States gallons, one gallon of which contains 231 cubic inches. Therefore the periphery of the drum is graduated with vertical lines 10 300 of which there are 231 such lines drawn on the complete periphery of the drum. A rotation of the drum from one line to another thus represents the dispensing of one cubic inch of gasoline. As the drum is designed to rotate ten times 15 to dispense ten gallons of gasoline, the drum is marked with a series of horizontal peripheral lines 301, there being ten of such lines and as the drum moves downwardly passing from one 20 horizontal line to another and making a complete rotation, one gallon of gasoline is dispensed for each horizontal line the drum moves downwardly. An initial or starting vertical line 300 is established on the drum and then calculations 25 are made as to the rotation of the drum to dispense gasoline in accordance with various prices. When the proper location is made the threaded sockets 290 are made in the drum. These sockets are numbered in any suitable manner, numbers 30 impressed on the drum, and then a chart is made, which chart may be secured to a suitable place inside of the cabinet, covered by a door, which may be opened so that an attendant may place the studs 291, 292 and 293 in their proper sockets in 35 accordance with the basic price of the gasoline. An example of a portion of a chart is given hereinafter having a price range of five to forty cents per gallon. The chart however should have changes in half-cent increases in price. This 40 is merely illustrative of the manner in which a chart may be prepared, as it will be noted a number of the intermediate prices and the numbers of the sockets are omitted. The numerals indicated for each of the studs or pins on the drum indicate the particular socket in which the ten cent, quarter dollar and half dollar stud will be placed to vend an amount of gasoline corresponding to the equivalent prices:

CHART

Studs

Price per gallon, cents	Short 10¢ No.	Medium 25¢ No.	Long 50¢ No.
5	117	147	157
5½	112	145	156
6	107	143	155
10	75	127	147
15	45	107	137
20	31	87	127
25	21	75	117
30	11	63	107
35	6	51	97
40	1	39	87

65 Various changes may be made in the details of the construction without departing from the spirit or scope of the invention as defined by the appended claims.

I claim:

1. In a fluid dispensing mechanism having an 70 electric switch for closing an electric circuit for initiating and continuing the flow of a fluid, said switch when opened discontinuing the flow of the fluid, an outlet valve for the fluid, a coin controlled mechanism having a first and a second 75 slidable part forming a coin pocket therebetween

whereby on a sliding movement of the first part the second part is moved through the engagement of the coin in the coin pocket, a pivoted arm connected to the valve, means on the second sliding part to move the arm downwardly to 5 thereby open the valve, a pivoted trigger lever connected to the same pivot as the pivot of the arm, an operative connection between the lever and the switch, a spring connected to the trigger lever tensioned for closing the switch, a hook 10 device pivoted on a fixed structure, a wedging device on the first sliding part to hold the hook device from engagement with the trigger lever, a spring to engage the hook device and the trigger lever on downward movement of the first sliding part, means to retain the second sliding part when moved downwardly with the valve open, means to return the second sliding part to its initial position and release the coin from the pocket, the return of the first sliding part releasing the hook device from the trigger whereby the spring closes the switch, means operative after dispensing a predetermined amount of fluid to release the second sliding part, means to return the second sliding part to its initial position and at the same time move the pivoted arm and the trigger lever to open the switch. 20 25

2. In a commodity dispensing machine having an electric switch for closing an electric circuit for initiating and continuing the dispensing of the commodity, said switch when opened discontinuing the vending of the commodity, a switch actuating means including in combination a movable slide having a detent on a first part, means operative on a second part 30 of the slide to move said slide from a first to a second position, a latch to engage the detent when the slide is in the second position, a pivoted arm movable with the said slide from its first to its second position, a pivoted trigger 35 lever, an operating connection from said trigger lever to the switch, a pivotally mounted hook device engageable with said trigger lever, a cam plate connected to the second part of the slide and engaging said hook device to hold the same 40 out of contact with the trigger lever when the slide is in its first position, means to engage the hook device and the trigger lever on the movement of the slide from its first to its second position and thereby retain the trigger lever in 45 its initial position with the switch open, a spring 50 engaging the trigger lever and tensioned to move said trigger lever to a second position to close the switch, the second part of the slide having the cam plate being movable from its second 55 to its first position to engage the hook device and release the same from the trigger lever whereby the spring moves the trigger lever from its first to its second position to close the switch, means operative after dispensing a predetermined amount of the commodity to release the latch from the detent, means to return the first part of the slide having the detent from its second to its first position whereby the said pivoted arm returns to its first position, interengaging 60 means between the pivoted arm and the trigger lever to return the trigger lever to its first position and hence open said switch. 65

3. Liquid dispensing apparatus, comprising a manually reciprocal slide-frame, a coin-slide de- 70 pressible therewith through the interconnection of a coin, a spring tending to retract said coin slide, means to retain said coin slide in its lowermost position, a pump including a liquid discharge pipe, a valve in said pipe, electrical means 75

- to actuate said pump including a controlling switch, a spring pressed trigger having operative connections to open and close said switch, a spring pressed arm retaining said trigger in its open switch position and engageable by said coin slide in its downward movements to release said trigger, retaining devices for said trigger engageable therewith on the downward movement of the frame, means operable on the return movement of the frame to free said trigger from said retaining devices to close said switch, link connections between said arm and said valve to open and close the same upon the respective downward and return movements of the coin slide, and means to release said coin slide upon the pumping of a predetermined quantity of liquid whereby the return movement of said coin slide admits of the like movements of said arm and trigger and the opening of said switch.
4. In a coin controlled mechanism, a structure having a coin chute slide with means cooperative therewith to form a coin pocket, a wedge-like detent connected to the slide having a sloping surface with a shoulder at the top, a latching device having a pivot on which it oscillates positioned transverse to the said slide, said latching device having a latching bar, means to depress the coin chute slide when a coin is in the coin pocket, means to retract the latching device to engage the detent whereby the wedge surface of the detent oscillates the said latching device outwardly, the retracting means engaging the latching bar with the shoulder of the detent, the latching bar having an opening adjacent the detent, a releasing means movable to engage the latching bar, said bar being movable transversely of the detent to disengage the shoulder from the latching bar, and means to return the coin chute slide to its original position on release of its detent.
5. In a coin controlled mechanism, a guide structure having a movable coin chute slide therein, a depressing slide slidably mounted parallel to the coin chute slide and forming therewith a coin pocket to receive a coin, means to depress the depressing slide and when there is a coin in the pocket thereby depress the coin chute slide, a retaining pin resiliently mounted on the coin chute slide, a retracting means for retracting the pin from the coin chute when the coin chute slide is in its elevated position but to release said pin when the slide moves downwardly, the said pin being positioned to extend into the said slide and support one or more coins located in the coin chute above the coin in the coin pocket, and means for temporarily retaining the coin chute slide in its depressed position while the depressing slide moves upwardly to release a coin from the coin pocket, the said pin being retracted when the coin chute slide moves upwardly to permit the lowermost coin now in the chute resting thereon to drop into the coin pocket.
6. Liquid dispensing apparatus comprising in combination a two part coin controlled mechanism arranged to be depressed through the interconnection of a coin, a latch to retain one part of said mechanism in its depressed position, means to return the second part of the mechanism, means to initiate the dispensing of the liquid actuated by said second part of said mechanism upon its return, a liquid quantity measuring device including a rotatable structure, means for bodily moving said structure longitudinally of its axis of rotation, adjustable trip-
ping means on said rotatable structure engage-

able with said latch to release said first part of the coin controlled mechanism from said latch, spring means to return said first part, and means released by the return of said first part to stop the flow of liquid.

7. In liquid dispensing apparatus, a plurality of pairs of coin slides, each said pair having a coin chute therebetween and movable in unison through the interconnection of a coin, said coin chutes being each arranged to receive coins of a different diameter, a detent projecting from one of said slides of each said pair at diverse distances in inverse relation to the coin size of the respective chute, and a latching bar common to all said detents and engageable with the furthest extending detent.

8. A commodity dispensing apparatus comprising in combination a coin controlled mechanism having a setting means employing a plurality of coin slides, each having a coin pocket for a coin of a different value, means to move all of the slides containing a coin in the coin pocket from a first to a second position, each coin slide having a detent, the detents being of variable length in accordance with the value of the coin to be received in the coin pocket of each slide, a rotatable and axially movable drum having a plurality of sockets positioned thereon in accordance with a series of prices of a unit of the commodity, a plurality of studs, each secured in a socket, the studs being of different length and corresponding to the coins receivable in the coin pockets, a tilting latch, said latch being positioned to be engaged by the longest detent of the coin slide moved with a coin in the coin pocket, the detent thereby holding such coin slide in its second position, means to dispense the commodity when the coin slide is so held by the latch, means to rotate and axially move the drum at a rate proportionate to the quantity of the commodity dispensed until a stud on the drum corresponding to the detent engaging the latch contacts such latch, the stud then causing the movement of the latch to release the detent held by the latch, means to return the released detent and the portion of the slide on which said detent is mounted to its first position and means to discontinue dispensing the commodity and means to return the drum to its first position.

9. In liquid dispensing apparatus, a pair of coin slides having a coin chute therebetween and movable in unison through the interconnection of a coin, one of said slides having a detent, and a pivotally mounted latch engageable with said detent to retain the slide in its advanced position, said latch being spring pressed inwardly to engage said detent and movable laterally to release the same.

10. In liquid dispensing apparatus, a pair of coin slides having a coin chute therebetween and movable in unison through the interconnection of a coin, one of said slides having a projecting detent, a spring pressed latch bar having a notch in its inner edge and pivotally movable inwardly to engage said detent, and movable laterally to release said detent through said notch.

11. In liquid dispensing apparatus, a spring pressed coin slide, a detent extending from said slide having an inclined cam face, and an inwardly spring pressed latching bar movable outwardly in contact with said cam face and having a groove in its inner edge to receive said detent.

12. In liquid dispensing apparatus, a spring pressed coin slide, a detent extending from said slide having an inclined cam face, an inwardly

5 spring pressed latching bar movable outwardly in contact with said detent cam face and having a groove in its inner edge to receive the detent, said bar having an opening in its groove to release said detent upon the lateral deflection of the bar.

13. In liquid dispensing apparatus, a plurality of parallel coin slides each having a projecting detent, the outer edges of said detents being spaced at different distances beyond the line of 10 said slides, and a latching bar common to all said detents and engageable with the furthest extending detent.

14. In a fluid dispensing mechanism, a drum 15 having a peripheral wall with a plurality of sockets therein and a plurality of studs in different sockets, each stud being of a different length, means to rotate the drum on its axis, one rotation for each unit of the fluid dispensed and 20 means to move the drum axially a unit distance for each unit of fluid dispensed whereby in dispensing a plurality of units of fluid the drum may complete a number of rotations and move longitudinally a plural number of the unit distances, 25 the said sockets being arranged to correspond to different quantities of fluid at different basic prices, a tripping mechanism and means actuated thereby to stop the flow of the fluid, the said tripping mechanism having means for positioning the same to engage a short or a longer stud in accordance with the quantity of fluid to be dispensed.

15. In a commodity dispensing apparatus, the combination of a rotatable and bodily movable 35 quantity registering device having a plurality of studs thereon positioned in accordance with the quantity of material to be dispensed for a specific monetary value, a setting means having detents each corresponding to a monetary value, a latch device engaged by one of said detents, selectively, 40 means to initiate the dispensing of the commodity when one of the detents is engaged with said latch, means to cause the rotation and the bodily movement of the quantity registering device at a rate proportionate to the dispensing of the commodity, the said detents and studs being respectively of such lengths as to position the latch when engaged by a detent in a position to be engaged by a stud in the rotation of the registering device, the stud being adapted to trip the 50 latch and release the latch from a detent and means to move the setting device having the released detent and a further means to discontinue the vending of the commodity.

16. In a commodity dispensing apparatus, the 55 combination of a rotatable and axially movable drum having a stud thereon positioned in accordance with the quantity of the commodity to be dispensed for a specific monetary value, a setting device having means to accommodate a coin corresponding to the monetary value of the commodity to be dispensed, means to move said setting means, said setting means having a detent corresponding to the monetary value of the coin 60 accommodated in the said setting means, a latch device engaged by said detent when the setting means is moved to bring the detent and the latch device into engagement, means to initiate the dispensing of the commodity operative only when 65 the detent and the latch are engaged, means to cause the rotation and bodily movement of the drum at a rate proportionate to the dispensing of the commodity, the said detent and stud being respectively of such length whereby the latch 70 held by the detent is contacted by the stud, the

stud tripping the latch from the detent, means to return the setting means to its original position when its detent is released, means to discontinue dispensing of the commodity and means to return the drum to its original position.

5

17. In liquid dispensing apparatus, the combination of a spring pressed latch, and a rotatable tripping means therefor comprising a drum mounted for rotary and longitudinal movements simultaneously, and a stop on said drum engageable to move said latch at predetermined points in the rotary and longitudinal movements of said drum.

10

18. In liquid dispensing apparatus, the combination with a spring tensioned reciprocative 15 coin slide including a detent, and a pivotally mounted latch engageable with said detent to retain the slide in its advanced position, of a rotatable shaft, means to actuate said shaft, a drum having a hub splined on said shaft formed 20 with exterior screw threads, a fixed nut in engagement with said hub, and a stop projecting from said drum to engage said latch to release said detent.

20

19. In liquid dispensing apparatus, an electrically driven pump, a rotary meter device to measure the flow of liquid therethrough from said pump, a rotatable shaft actuated by said meter, a drum having a hub splined on said shaft and formed with exterior screw threads, and a 30 fixed nut in screw threaded engagement with said hub whereby said drum will rotate with and simultaneously advance longitudinally of said shaft.

25

20. In liquid dispensing apparatus, a rotatable 35 shaft, a drum having a hub splined to said shaft and formed with exterior screw threads, a fixed nut in screw threaded engagement with said hub, and stop devices adjustably secured to the exterior wall of said drum.

40

21. In liquid dispensing apparatus, a rotatable shaft, a drum having a hub splined to said shaft and formed with exterior screw threads, a fixed nut in screw threaded engagement with said hub, and stop devices projecting from the exterior wall of said drum and securable thereto in 45 positions spaced apart in lines parallel to the axis of rotation of the drum distances equal to the distances between the pitch-lines of said screw threads.

45

22. In liquid dispensing apparatus, a rotatable shaft, means to actuate said shaft, a drum having a hub splined on said shaft formed with exterior screw threads, and a fixed nut in screw threaded engagement with said hub whereby said drum will partake of the rotary motion and simultaneously advance longitudinally of said shaft.

50

23. In a fluid dispensing mechanism, a drum having a cylindrical wall with a plurality of vertical lines spaced thereabout to indicate on rotation of the drum a dispensing between one vertical line and another of a minor proportion of a gallon of liquid, the drum also having a plurality of horizontal lines positioned at an equal distance apart to represent in dispensing a travel 60 of the drum bodily on its axis a distance for one gallon corresponding to the space between adjacent horizontal lines, a series of sockets positioned in the drum corresponding to various vertical and horizontal lines, there being a sufficient number 65 of sockets to designate the vending of different quantities of liquid at varying basic prices, a plurality of studs in different sockets, each stud being of a different length, means to rotate the drum on its axis one rotation for each gallon of 70

55

- liquid dispensed and means to move the drum axially the distance between two adjacent horizontal lines for each gallon of liquid dispensed whereby in dispensing a number of gallons of liquid the drum may rotate a number of times and be moved longitudinally on its axis a distance equal to that between a plurality of the horizontal lines, a tripping mechanism and means actuated thereby to stop the flow of liquid, the said tripping mechanism having means for positioning the same to engage a short or a longer stud in accordance with the quantity of liquid to be dispensed.
24. In liquid dispensing apparatus, a rotatable drum having a cylindrical wall provided with evenly spaced lines parallel to its axis of rotation and a plurality of spaced circumferential lines, means to rotate said drum, and means to move said drum bodily during such rotation, said circumferential lines being spaced apart the distance equal to the bodily movement of said drum in each revolution.
25. In liquid dispensing apparatus, a rotatable drum having a cylindrical wall provided with evenly spaced lines parallel to its axis of rotation and a plurality of spaced circumferential lines, means to rotate said drum, means to move said drum bodily during such rotation, said circumferential lines being spaced apart the distance equal to the bodily movement of said drum in each revolution, said drum having a plurality of sockets formed therein at the intersection of said lines, and a plurality of studs seated in said sockets and protruding from said cylinder wall.
26. In liquid dispensing apparatus, a coin actuated setting device having a detent, a latch engaging said detent when the setting device is actuated, means to initiate the dispensing of the liquid operative when the detent and latch are

engaged, a rotatable and axially movable drum, means to cause the rotation and axial movement of the drum at a rate proportionate to the dispensing of the liquid, a stud on said drum positioned in accordance with the quantity of liquid to be dispensed, said stud tripping the latch in the rotative and axial movements of the drum to release said detent, means to return the setting device to its original position, and means to discontinue the dispensing of the liquid.

27. In liquid dispensing apparatus, the combination of a spring pressed latch, and a rotatable tripping means therefor comprising a drum mounted for rotary and longitudinal movements simultaneously, and a stop on said drum engageable to move said latch at predetermined points in the rotary and longitudinal movements of said drum, and means controlled by tripping of the spring pressed latch to stop the rotation of the drum and hence its longitudinal movement and means having a driving connection to the drum to reverse the rotation of the drum and reverse the longitudinal movement of the drum to return such drum to its original position.

28. In liquid dispensing apparatus, a rotatable shaft, a drum having a hub splined to said shaft and formed with exterior screw threads, a fixed nut in screw threaded engagement with said hub and stop devices adjustably secured to the exterior wall of said drum, a driving means for the said rotatable shaft including a clutch, means controlled by said stop devices to actuate said clutch to release the rotational drive of said shaft and means to urge and rotate said shaft in a reverse direction to reverse the rotation of the drum and hence reversely threading the drum in relation to the fixed nut to return the drum to its original position.

EMIL C. BABER.
